Seth A. Crone INVENTOR

BY Charles C. Gill
ATTORNEY

UNITED STATES PATENT OFFICE.

SETH A. CRONE, OF EAST ORANGE, NEW JERSEY.

RAILWAY BRAKE BEAM.

Application filed July 31, 1922. Serial No. 578,595.

To all whom it may concern:

Be it known that I, SETH A. CRONE, a citizen of the United States, and a resident of East Orange, in the county of Essex and 5 State of New Jersey, have invented certain new and useful Improvements in Railway Brake Beams, of which the following is a specification.

The invention pertains to trussed beams 10 for railway cars and especially to novel means for securing the strut and compression member in rigid relation to each other.

My invention resides in a novel construction involving a swiveled or pivotally 15 mounted locking dog carried by the strut and adapted to be forced into binding relation with the compression member, said locking dog having a portion to be bent outwardly against the compression member 20 after the dog has been forced into engagement therewith for retaining the dog in its locking position.

One object of the present invention is to dispense with wedges and other separate 25 parts usually employed for binding the strut and compression member in rigid relation to each other.

In accordance with my invention the strut carries the locking dog as a portion thereof, 30 and said locking dog is not separable from the strut but is always in position for use.

A further purpose of the invention is to provide very strong and durable means for 35 securing the strut and compression member together, the locking dog which I apply to the strut being either of malleable casting or steel forging and capable of being driven to position by means of a hammer without becoming distorted or broken.

40 The invention will be fully understood from the detailed description hereinafter presented, reference being had to the accompanying drawings, in which:

Fig. 1 is a side elevation, partly broken away, of a brake-beam showing the swiveled locking dog carried by the strut in locking engagement with the compression member of the brake-beam;

Fig. 2 is a similar view of the same showing the locking dog in an initial position prior to being engaged with the compression member;

Fig. 3 is a transverse section, partly broken away, through the beam and taken 55 on the dotted line 3-3 of Fig. 1;

Fig. 4 is a view in front perspective of

the locking dog detached or separate from the strut;

Fig. 5 is a side elevation of the same;

Fig. 6 is a bottom view of the same, being a projection downwardly from Fig. 5;

Fig. 7 is a front perspective view of a modified form of locking dog embodying my invention, this dog being made from forged steel instead of malleable casting, according to which the locking dog of Figs. 1 to 6 inclusive is made;

Fig. 8 is a side elevation of the locking dog shown in Fig. 7, being a projection taken from the right hand edge of Fig. 7;

Fig. 9 is a bottom projection taken from the lower side of Fig. 8;

Fig. 10 is a top view of the blank from which the locking dog of Figs. 7, 8 and 9 is formed, and

Fig. 11 is an edge view of the same, being a projection taken from the lower edge of Fig. 10.

In the drawings 10 designates a channel-shaped compression member of a brake-beam, and 11 the strut, which may be made from a bar of forged metal forming two integral sides 12 to receive between them, as usual, the brake lever, not shown, and providing at its folded middle portion a yoke 80 or loop 13 which extends transversely upon and closely receives the channel member 10, which may be of any approved or suitable cross section.

The compression member 10 and strut 11 may be modified in construction in various ways without departure from my invention, which resides more particularly in the combination with the strut and compression member of a brake-beam, of a pivoted locking dog 14 carried by the strut and adapted, after the assembly of the compression member and strut, to be forced into locking engagement with the compression member, thereby securely binding the strut and compression member in rigid relation to each other.

The sides of the strut forwardly of the flanges of the compression member are parallel, as at 15, and extending through and between these portions of the sides of the strut is a strong rivet or the like 16 upon which the locking dog 14 is swiveled, said locking dog being adapted to turn on the rivet 16 and also to be swung between the flanges of the compression member 10.

The locking dog 14 shown in Figs. 1 to 6

inclusive is in one integral malleable casting and somewhat triangular in side elevation, said dog being formed at one end with the sleeve 17 through which the rivet 16 is 5 passed, and at its other end with an arcuate section 18 extending the full width of the dog and being eccentric to the center of the rivet 16. The arcuate section 18 is connected with the sleeve 17 by the side members 19 10 of the dog and also by means of a central web 20, shown by dotted lines in Fig. 5. The sides 19 of the dog extend beyond the inner end of the arcuate section 18, as shown in Fig. 4, and said section 18 is formed with 15 a projecting tongue 21 which is free of the sides 19 and extends beyond the same. In the initial condition of the locking dog, the tongue 21 may extend on the same arc as the section 18 of said dog, as shown in Figs. 20 2 and 5.

The dog 14 is carried by the strut, being permanently mounted on the rivet 16 which is headed at its opposite ends at the outer sides of the side members of the strut, and 25 on the initial assembly of the compression member 10 and strut 11, the locking dog 14 may be in the general position in which it is illustrated in Fig. 2, said dog then being entirely free of the compression member. 30 After the compression member and strut have been assembled by the passage of the compression member through the yoke 13 of the strut or the slipping of said yoke along said compression member, the strut and 35 compression member must be secured together, and to accomplish this purpose I force, by hammering or otherwise, the dog 14 to turn outwardly against the inner surface of the web of the compression member, 40 or to the position in which said dog is shown in Fig. 1, the arcuate section 18 then being firmly wedged against the compression member. In order to prevent reverse motion of the locking dog 14 from its position 45 shown in Fig. 1 to that shown in Fig. 2, due to the jarring of the mechanism, I provide the dog with the tongue 21 which, after the dog has been driven to operative position or from the position shown in Fig. 2 to that 50 shown in Fig. 1, is bent outwardly against the web of the compression member or to the position shown by dotted lines in Fig. 1 and by solid lines in Fig. 3. The bending of the tongue 21 outwardly against the web 55 of the compression member may be performed by means of a hammer or other suitable tool. After the tongue 21 has been bent outwardly against the compression member, the dog will be incapable of turning re- 60 versely from engagement with said member, said tongue by reason of its projection preventing the reverse turning of the dog on the rivet 16. The web 20 is on the central line of the rivet 16, and I so proportion the 65 size of the dog that when the dog is driven

to its binding or operative position or from the position shown in Fig. 2 to that shown in Fig. 1, the plane of the web 20 does not pass into the central line of the strut and rivet, but inclines to one side thereof, as 70 shown by dotted lines in Fig. 1, so that by no possibility may the dog be driven from one side to the other of the rivet 16. The arcuate section 18 being eccentric to the rivet 16 serves as a wedge to bind against 75 the web of the compression member and at the same time also prevents the dog from being carried over the center of the rivet 16. The arcuate section 18 serves to prevent the dog having undue movement inwardly 80 against the web of the compression member and the tongue 21 when bent outwardly against said web, prevents said dog from, due to jarring or otherwise, having a reverse movement towards its initial position. The 85 dog 14 when once positioned thus serves to securely bind the compression member and strut together the arcuate surface 18 of the dog binding against the web of the compression member and the sleeve 17 against 90 the rivet 16.

The ends of the sleeve 17 are cut away or in part discontinued, as at 22, so that said sleeve at its end portions may not interfere with the forward edges of the flanges of 95 the compression member 10, while at the same time portions of the ends of said sleeve, where not cut away or discontinued, extend outwardly into near relation to the inner surfaces of the sides of the strut, as shown 100 in Fig. 3.

The construction of the dog shown in Figs. 1 to 6 inclusive is such as to produce a dog possessing great resisting power and of sufficiently durability to permit said dog to be hammered into its operative position and act with entire efficiency. I make the tongue 21 of somewhat considerable length, as shown, so that it may be bent outwardly against the compression member without 110 danger of the tongue being broken off. Since the dog is of malleable casting, the tongue may be bent outwardly against the compression member without danger and may also be bent inwardly from said compression member at any time it may be desired to remove the strut from the compression member. I do not of course limit my invention to the length of the tongue 21, the essential consideration being that the tongue 21 shall be 115 sufficiently long to prevent reverse motion of the dog 14.

In Figs. 7 to 11 inclusive I show a dog 23 possessing all of the functions of the dog 14 shown in Figs. 1 to 6 inclusive, but made from a forging instead of from a malleable casting. The dog 23 is formed from a blank 24 of the form shown in Fig. 10, said blank being folded or U-ed to provide the corresponding opposite side members 25, arcu- 120 125 130

ate section 26 and tongue 27. The side members 25 are apertured, as at 28, to receive the rivet 16. The arcuate surface 26 of the dog 23 corresponds with the arcuate surface 18 of the dog 14, and the tongue 27 of the dog 23 corresponds in function with the tongue 21 of the dog 14, but is made shorter than said tongue 21 because the dog 23 being of forged metal, the tongue 27 may be bent more frequently, with less danger of breakage, than a short malleable tongue.

In practical use the locking dog 23 has the same operation as the malleable cast dog 14, and possesses some advantages over the dog 14 in respect to the forged metal affording adequate strength with less weight of material and the forged dog being very convenient to manufacture.

The arcuate surface 26 is, corresponding-
ly with the arcuate surface 18 of the dog 14, eccentric to the center of the rivet 16 or is on a line tangential to a circle struck from the center of the rivet 16, thereby assuring an effectual wedge-action when the dog is driven into its operative position.

It is usual in struts to provide a rivet forwardly of the twisted portions of the sides of the strut for connecting said sides. In accordance with my invention the rivet 16 serves to effectually connect the sides of the strut forwardly of the compression member and at the same time is so positioned as to cooperate with the locking dog in securing a rigid relation of the strut and compression member to each other.

The locking dog is carried by the strut, and hence there is no danger of the locking feature of the brake-beam being lost or misplaced. The locking dog may be of other constructions than those shown in the drawings, and hence my invention is not limited to the details of the construction of the locking dog further than the scope of the appended claims may require. I believe my invention to be broadly new in providing a swinging locking dog carried by a strut to be forced into wedging engagement with the compression member of a brake-beam, and I desire to secure adequate protection for my invention.

What I claim as my invention and desire to secure by Letters Patent, is:

1. In a brake-beam having a compression member and a strut connected therewith, means for binding the compression member and strut together comprising a locking device at one end pivoted on the strut and adapted at its other end to be driven into binding relation with said compression member, said device being adapted for lateral swinging movement and at its outer initially free end being adapted to be wedged against the inner surface of the compression member by blows directed laterally against one edge of said end.

2. In a brake-beam having a compression member and a strut connected therewith, means for binding the compression member and strut together comprising a rivet connecting the sides of the strut forwardly of the compression member and a locking device at one end mounted to swing on said rivet and adapted at its other end to be driven into binding relation with said compression member, said locking device then acting as a wedge between and binding against both said rivet and the inner surface of the compression member, and said device being adapted for lateral swinging movement at its initially free end and to be given its operative position by blows directed laterally against one edge of said end.

3. In a brake-beam having a compression member and a strut connected therewith, means for binding the compression member and strut together comprising a locking device at one end pivoted on the strut and adapted at its other end to be driven into binding relation with said compression member, said locking device having a tongue to be bent against said compression member to thereby prevent reverse motion thereof from its operative position.

4. In a brake-beam having a compression member and a strut connected therewith, means for binding the compression member and strut together comprising a rivet connecting the sides of the strut forwardly of the compression member and a locking device at one end mounted to swing on said rivet and adapted at its other end to be driven into binding relation with said compression member, said locking device having a forward tongue to be bent against said compression member to thereby prevent reverse motion of the device from its operative position.

5. In a brake-beam having a compression member and a strut connected therewith, means for binding the compression member and strut together, comprising a swinging wedge device pivotally mounted at one end on and carried by the strut and having an arcuate surface at its other end to be driven against the compression member with binding effect, said arcuate surface extending lengthwise of the compression member and tangentially to the inner longitudinal surface of the web of said member, and said device being adapted for lateral swinging movement at its arcuate initially free end and to be given its operative position by blows directed laterally against one edge of said end.

6. In a brake-beam having a compression member and a strut connected therewith, means for binding the compression member and strut together comprising a swinging wedge device pivotally mounted at one end on and carried by the strut and having an

arcuate surface at its other end to be driven against the compression member with binding effect, said arcuate surface being eccentric to the pivoted end of said device, and said device having a forward tongue to be bent against the compression member to thereby prevent reverse motion of said device.

7. In a brake-beam having a compression member and a strut connected therewith, means for binding the compression member and strut together comprising a rivet connecting the sides of the strut forwardly of the compression member and a swinging wedge-dog pivotally mounted at one end on said rivet and adapted at its other end to be driven into binding relation with said compression member, the outer initially free end of said dog being elongated and tangential to the inner longitudinal surface of the compression member, and said dog being adapted to be given its operative position by blows directed laterally against one edge of said end, and said dog when in operative position acting as a wedge between and binding against both said rivet and the inner surface of the compression member.

8. In a brake-beam having a compression member and a strut connected therewith, means for binding the compression member and strut together comprising a rivet connecting the sides of the strut forwardly of the compression member and a swinging wedge-dog pivotally mounted at one end on said rivet and adapted at its other end to be driven into binding relation with said compression member, said compression member being of channel beam type and said dog being adapted to swing between the flanges thereof and engage the inner surface of the web of the beam, and said dog having a forward tongue to be bent against said web to thereby prevent reverse motion of said dog.

9. In a brake-beam having a compression member and a strut connected therewith, means for binding the compression member and strut together comprising a rivet connecting the sides of the strut forwardly of the compression member and a swinging wedge-dog pivotally mounted at one end on said rivet and adapted at its other end to be driven into binding relation with said compression member, said compression member being of channel beam type and said dog being adapted to swing between the flanges thereof and engage the inner surface of the web of the beam, and said dog at its outer end having a curved surface to engage said web and which surface is eccentric to the pivot point of the dog, and tangential to the inner longitudinal

surface of said web, and said dog being adapted to be given its operative position by blows directed laterally against one edge of said end, and said dog when in operative position acting as a wedge between and binding against both said rivet and the inner surface of the compression member. 70

10. In a brake-beam having a compression member and a strut connected therewith, means for binding the compression member and strut together comprising a rivet connecting the sides of the strut forwardly of the compression member and a swinging wedge-dog pivotally mounted at one end of said rivet and adapted at its other end to be driven into binding relation with said compression member, said dog being in one integral piece and having sides and an arcuate section connecting said sides and constituting the outer end of the dog, said arcuate section being elongated longitudinally of the compression member and tangential to the inner longitudinal surface thereof, and said dog being adapted to be given its operative position by blows directed laterally against one edge of said end, and said dog when in operative position acting as a wedge between and binding against both said rivet and the inner surface of the compression member. 80

11. In a brake-beam having a compression member and a strut connected therewith, means for binding the compression member and strut together comprising a rivet connecting the sides of the strut forwardly of the compression member and a swinging wedge-dog pivotally mounted at one end on said rivet and adapted at its other end to be driven into binding relation with said compression member, said dog being in one integral piece and having sides and an arcuate eccentrically disposed section connecting said sides and constituting the outer end of the dog. 100

12. In a brake-beam having a compression member and a strut connected therewith, means for binding the compression member and strut together comprising a rivet connecting the sides of the strut forwardly of the compression member and a swinging wedge-dog pivotally mounted at one end on said rivet and adapted at its other end to be driven into binding relation with said compression member, said dog being in one integral piece and having sides, an outer arcuate end connecting said sides and a forwardly extending tongue to be bent into engagement with the compression member. 110

Signed at New York city, in the county of New York and State of New York, this 15th day of July, A. D. 1922.

SETH A. CRONE.
